Des. 194,617
Patented Feb. 19, 1963

194,617

TOY BARN

Bill Markham, Los Angeles, Calif., assignor to Lakeside Industries, Inc., Minneapolis, Minn., a corporation of Delaware

Filed Aug. 3, 1962, Ser. No. 71,164

Term of patent 14 years

(Cl. D34—15)

FIG. 1

FIG. 5

FIG. 2

FIG. 3

FIG. 4

FIG. 1 is a right front perspective view of a toy barn embodying my new design;

FIG. 2 is a front elevational view thereof;

FIG. 3 is a sectional view thereof taken as on line 3-3 in FIG. 2;

FIG. 4 is an end elevational view thereof taken as on line 4-4 in FIG. 2; and

FIG. 5 is a right rear perspective view thereof.

I claim:

An ornamental design for a toy barn, as shown.
